UNITED STATES PATENT OFFICE.

HARRY M. WILLIAMS, OF BLOOMINGTON, ILLINOIS.

RECODER.

SPECIFICATION forming part of Letters Patent No. 567,017, dated September 1, 1896.

Application filed November 26, 1895. Serial No. 570,229. (No model.)

To all whom it may concern:

Be it known that I, HARRY M. WILLIAMS, a citizen of the United States, residing at Bloomington, in the county of McLean and State of Illinois, have invented certain new and useful Improvements in Recorders; and I do hereby declare the following to be a full, clear, and exact description of the invention, such as will enable others skilled in the art 10 to which it appertains to make and use the same.

This invention relates to improvements in recorders, the objects in view being to produce a simply-constructed recorder, the same 15 being adapted to afford a convenient means for automatically recording and preserving for subsequent inspection and comparison with the cash in the till the record of all cash-sales made.

20 Other objects and advantages of the invention will hereinafter appear, and the novel features thereof will be particularly pointed out in the appended claims.

Referring to the drawings, Figure 1 is a 25 transverse vertical section and a partial side elevation of my combined recorder and till-alarm, the till being withdrawn. Fig. 2 is a plan view, the desk-lid being removed to show the internal mechanism.

30 Like numerals indicate like parts in both figures of the drawings.

In practicing my invention I employ a desk or case 1, the same being subdivided horizontally by a partition 2, thus producing an upper compartment 3 and a lower compartment 4, the whole being covered by a hinged lid 5, having an opening 6 at a suitable point therein. The lid is of course provided with a suitable lock, the key to which is carried by the 40 proprietor or other authorized person.

Rigidly secured upon the partition 2, and therefore within the upper compartment 3, is a pair of vertical standards 7, connected at their upper ends by a horizontal and therefore transverse plate or table 8, that is located directly under the opening 6 in the desk-lid and corresponds in proportion thereto. The standards 7 are provided with rearward extensions or arms 9 at their rear edges and at 50 their front edges with similar extensions or

arms 10. The rear arms form bearings for a rotatable shaft 11, designed to serve as a reel, as will hereinafter appear, and this shaft, which I shall term the "reel-shaft," is extended at one end beyond its bearing and is there 55 provided with a ratchet-wheel 12. From one of the arms 10 there extends a conical bearing-point 13, and through an opening in the opposite or companion arm there extends a similar bearing-point 14, the same being af- 60 fixed to the free end of a flat spring 15, secured to the outer side of the said arm 10. These bearing-points 13 and 14 are designed to engage with the correspondingly-counter-sunk ends of a core, usually employed in rolls 65 of recording-paper 16, and by the construction shown the core may be removed when the paper has become exhausted therefrom.

Pivoted upon a stud 17, extending from that standard 7 at the side of which the ratchet-wheel 12 is located, is a yoke 18, the ends of which are perforated and loosely receive a plunger-rod 19. Arranged around the rod is a coil-spring 20, the tendency of which is to force the rod yieldingly to the front. A 70 greater length of the rod lies in front of the pivot-point of the yoke, and hence said rod is heavier in front and normally falls. The extent of its fall is limited by the rear edge of an opening 21, formed in the partition 2, 75 and through which the lower end of the rod passes into the lower compartment 4 of the desk, where said rod is laterally bent, as indicated at 22, dotted lines, Fig. 2.

Pivoted, as at 23, to the rod at a point in 80 rear of the pivot 17 of the yoke is a rearwardly-disposed bifurcated gravity-pawl 24, the bifurcation of said pawl loosely embracing the ratchet-wheel 12. In advance of its pivot the pawl is loosely connected to the 85 rear end of the plunger-rod 19 by a keeper 25, so that the pivotal movement of the pawl independent of the rod is limited.

In the lower compartment in suitable slides 27 is arranged the till 28, the same having 90 its interior subdivided in a desired manner for the accommodation of different denominations of money. One side of the till has its side wall extended beyond its rear wall, and said side wall has its upper edge chan- 95 100

neled or cut away, producing a groove 29, which terminates near the front of the drawer or till in an abrupt shoulder 30, in advance of which the bottom of the groove is provided 5 with a slight rise or incline 31. So also at the rear end is said groove 29 inclined at its bottom, as at 32.

Arranged upon a suitable post or bracket 33, secured to the rear wall of the desk and 10 within the compartment 4, is a curved spring-buffer 34, against which the rear wall of the till or drawer abuts when said till or drawer is closed, the spring yielding to compression and serving when the drawer is released 15 to throw the same forward to a partially open position.

This completes my invention, and the operation thereof may be briefly described as follows: A roll of paper being arranged between 20 the bearing-points 13 and 14 in the manner heretofore described, the leading end thereof is carried on the plate or table 8 and made fast to the reel-shaft 11. The weighted front end of the plunger-rod being normally depressed, it will be obvious that the rear end carrying the pawl will be normally elevated. When a sale is made, it is recorded by the salesman upon the record-strip, and the money deposited in the till or drawer, after 25 which the drawer is closed and in the act of closing the forward end of the plunger rod 19 rides up the incline 32 of the drawer or till, enters the groove 29, moves up the incline 31, and finally abuts against the shoulder 30 of 30 said groove. The entrance of the front end of the plunger-rod into the groove serves to raise said front end against its normal tendency and therefore lower the rear end of said rod, thus by the presence of the keeper 35 25 causing the pawl 24 to become lowered into contact with the teeth of the ratchet-wheel 12, and to be held in such contact in a positive manner. When the shoulder 30 of the drawer contacts with the front end of the plunger-rod, which, it will be understood, is subsequent 40 to the lowering of the rear end of the pawl into engagement with the teeth of the ratchet-wheel, the said plunger-rod is by the further inward movement upon the part of 45 the drawer caused to recede against the tendency of its spring 20, and with it is moved the pawl a sufficient distance to cause the ratchet-wheel to rotate the distance of one tooth. This serves to reel up the record of 50 55 the purchase upon the reel-shaft. At night, at the end of business, the proprietor or other authorized person opens the desk-lid with his key and withdraws that portion of the paper upon which the record is made and computes 60 the amount of cash-sales and compares the same with the cash contained in the till or drawer. He subsequently readjusts the leading end of the recording-strip and relocks the desk for the next day's business, and by such 65 60 relocking obviates any danger of the mechanism containing the record being tampered with.

From the foregoing description, in connection with the accompanying drawings, it will be apparent that I have provided a convenient and simple construction of recorder, whereby an accurate account of cash received 70 may be recorded.

I do not limit my invention to the precise details of construction herein shown and described, but hold that I may make such changes therein as experience may suggest and mechanical skill dictate without departing from the spirit of my invention or sacrificing any of its advantages. 75 80

Having described my invention, what I claim is—

1. The combination with the desk or casing, the roll-supports, the reel-shaft and the intermediate paper support or table, of the reciprocating and pivotally-supported forwardly-spring-pressed rod, a pawl loosely pivoted to said rod in rear of its pivot, a ratchet-wheel arranged on the reel-shaft and adapted to be engaged by the pawl, of a drawer having a shoulder and an inclined surface for raising and reciprocating the rod against the tension of its spring, substantially as specified. 85

2. The combination with the desk or casing, the roll-supports, the reel-shaft and the intermediate paper support or table, of the reciprocating and pivotally-supported forwardly-spring-pressed rod, having a lower weighted bent end, a stop for the same to limit its downward movement, a pawl loosely pivoted to said rod in rear of its pivot, a ratchet-wheel arranged on the reel-shaft and adapted to be engaged by the pawl, of a drawer having a rearwardly-extended side 105 wall 28, in the upper side of which is formed the front and rear inclines 31 and 32, and at the end of which is formed the shoulder 30, said groove and inclines being slightly above the normal position of the lower end of the rod, and the keeper 25 between the rear end of the rod and the pawl, substantially as specified. 110

3. The combination with the desk or casing transversely subdivided by a horizontal partition into upper and lower compartments, said partition having near its front an elongated opening, a drawer arranged in the lower compartment and having one of its side walls provided with an inclined surface 31 terminating in a shoulder 30, of the standards 7 arranged on the partition at opposite sides of an opening 6 with which the lid of the case is provided, said standards being connected by the transverse plate 8 and provided at 115 120 125 their front and rear sides with the arms 10 and 11 respectively, the roll-holders arranged in the front arms, the reel-shaft journaled to the rear arms, the ratchet-wheel arranged on said shaft, the yoke 18 pivoted centrally as 130 at 17 to one of the standards 7, the plunger-rod arranged for reciprocation in said yoke and having a greater portion in front of the same and extending down through and below

the opening in the partition, the edge of
which limits its downward movement, the
coil-spring arranged upon the rod within the
yoke, the bifurcated pawl pivoted on the rod
5 beyond the yoke and engaging the ratchet-
wheel, and the keeper 25 connecting the pawl
and plunger-rod, substantially as specified.

In testimony whereof I affix my signature
in presence of two witnesses.

HARRY M. WILLIAMS.
